Primary Examiner—Charles A. Rademaker

(74) Attorney, Agent, or Firm—George C. Rondeau, Jr.;
Davis Wright Tremaine LLP(57) **CLAIM**The ornamental design for a powerline communications
device, as shown and described.**DESCRIPTION**

FIG. 1 is a front perspective view of a powerline communications device showing our new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan view thereof;

FIG. 7 is a bottom plan view thereof;

FIG. 8 is a front perspective view of a modified embodiment
of the design shown in FIGS. 1 through 7;

FIG. 9 is a front elevation thereof;

FIG. 10 is a rear elevation thereof;

FIG. 11 is a left side elevation thereof;

FIG. 12 is a right side elevation thereof;

FIG. 13 is a top plan view thereof; and,

FIG. 14 is a bottom plan view thereof.

The broken line showing of environment in the figure
drawings is for illustrative purposes only and forms no part
of the claimed design.**1 Claim, 14 Drawing Sheets***Fig. 1*
